UNITED STATES PATENT OFFICE.

GEORGE WILLIAM THEXTON, OF MILWAUKEE, WISCONSIN.

LIQUID-FUEL BURNER.

1,129,140.

Specification of Letters Patent. Patented Feb. 23, 1915.

Application filed February 9, 1914. Serial No. 817,487.

To all whom it may concern:

Be it known that I, GEORGE WILLIAM THEXTON, a British subject, residing at Milwaukee, in the county of Milwaukee and State of Wisconsin, have invented certain new and useful Improvements in Liquid-Fuel Burners, of which the following is a specification, reference being had to the accompanying drawing, forming a part thereof.

This invention relates more particularly to burners having a wick tube or generating chamber or section and a vertically movable mixing and combustion chamber or section located above the wick tube or generating chamber.

The main objects of the invention are to provide for an intimate and thorough mixture of air with the fuel vapor or gas in the requisite proportions to insure complete and perfect combustion of the fuel without smoke or odor; to produce a hot blue flame with kerosene or other liquid fuel for cooking and other purposes; to prevent the formation and deposit of carbon; and generally to improve the construction and operation of burners of this class.

It consists in the construction, arrangement and combination of parts as hereinabove particularly described and pointed out in the claims.

In the accompanying drawing like characters designate the same parts in the several figures.

Figure 1 is a vertical medial section of a burner embodying the invention; Fig. 2 is a vertical section on a reduced scale of a stove frame as equipped with a burner of this kind, the upper part of the burner being shown in elevation and the lower part in vertical medial section; and Fig. 3 is a plan view of one of the spiders or guides in the wick tube for the rod which carries the upper part of the burner.

Referring to Figs. 1 and 2, the burner comprises a vapor or gas generating section and a vertically movable vapor or gas and air mixing and combustion section.

The lower or generating section may consist as shown, of a double walled annular wick tube and liquid fuel chamber *a*, which is closed at the lower end and usually mounted as shown in Fig. 2, on a suitable base *b*, such as the baseplate of a stove frame. The wick tube or fuel chamber is provided with

spiders or cross pieces *c*, one of which is shown in Fig. 3, having central openings to receive and guide a vertical rod *d*, which carries the upper section of the burner, as hereinafter explained.

The upper section of the burner comprises coaxial perforated tubes *e*, forming an annular mixing and combustion chamber *f*, which is arranged to register at its lower end with the upper open end of the wick tube or fuel chamber *a*, as shown in Fig. 1. The outer tube *e* is perforated with small holes its entire length, or approximately so, while the inner tube has an imperforate belt or zone *g*, adjacent to its upper end. The inner tube *e* is fitted and held at its ends in marginal folds or grooves of circular heads *h* and *i*.

A central air tube *j*, of smaller diameter than the inner tube *e* and open at its lower end, is fitted and held at the ends in circular recesses pressed or formed in the heads *h* and *i*, which close the annular space between and at the ends of said tubes. The lower head *i* is formed with a central air inlet opening *k*, and the upper head *h* is formed with a number of vent or outlet openings *l*, for admitting air into the lower end of the tube *j* and allowing a portion of it to escape from the upper end of said tube.

A cap *m*, fitted to and seated against the under side of the head *i* around the opening *k* therein and constituting in effect an extension of the air tube *j* below said head, is formed in the sides with air inlet openings *n*. The tube *j* is formed in the sides above and adjacent to the lower head *i*, with openings *o*, to allow the greater portion of the air entering said tube to pass therefrom into the annular space between it and the inner tube *e*. The rod *d*, which passes upwardly through central openings in the cap *m* and in the upper head *h*, is formed or provided with a collar or shoulder *p*, below and engaging with the cap *m*, and is secured at its upper end in the upper head *h* by a nut *q*, or other suitable means, thereby tying the cap and heads together and holding the heads in engagement with the inner tube *e* and the tube *j*.

A cylindrical shield *r* surrounding the outer tube *e* and extending some distance above and below the same, is secured with said tube to the inner tube *e* by bolts or rivets *s* and spacing sleeves *t*. The shield *r*,

which is open at its lower end, is preferably contracted at its upper end, which is open above the tubes *e*.

To facilitate connecting the burner with a fuel supply pipe and removing the same therefrom for the purpose of cleaning or repairing the burner, the following coupling means are provided: The wick tube or fuel chamber *a*, is provided, as shown in Figs. 1 and 2, with a nipple *u*, which has a semi-spherical end and lugs *v* on opposite sides thereof. The supply pipe *w* is formed in one side with an opening and a semi-spherical seat around the opening in which the end of the nipple is fitted. A hooked and forked clamp *x*, removably fitting over the pipe *w* and adapted to engage with the lugs *v*, is provided with a set screw *y*, which by engagement with the pipe, is adapted to force and hold the spherical end of the nipple tightly against its seat in the pipe.

The wick tube or fuel chamber *a*, is to be provided with a wick, which is adjusted for lighting, extinguishing and regulating by the usual or any suitable means (not shown).

The upper section of the burner is lifted for lighting the wick, and is held in an elevated position out of contact with the burner tube and wick, as shown in Fig. 2, by the following means: A lever *z*, fulcrumed to a lug on the under side of the base *b*, projects at its inner end underneath and is adapted to engage with the lower end of the rod *d*. At its outer end said lever is provided with a pivoted handle or operating and locking piece *3*, which extends upwardly therefrom through a slot or opening in the base *b* and is formed with a notch or shoulder adapted by engagement with the base when the lever is depressed, to hold the upper section of the burner in an elevated position out of contact with the wick tube and wick.

In the operation of the burner, the upper section thereof is lifted, as shown in Fig. 2, to light the wick. The wick having been lighted and properly adjusted, the upper section is released by pushing the operating piece *3* backward out of engagement with the base *b*, thus permitting the perforated tubes *e* forming the mixing and combustion chamber, to descend and rest upon the upper ends of the walls of the wick tube *a*, as shown in Fig. 2. Air passing upwardly through an opening in the base *b*, wick tube *a* and openings *n* in cap *m*, enters the tube *j* through opening *k* in the lower head *i*, and passing thence through the openings *o* into the annular space around said tube, enters the mixing and combustion chamber *f* through the small holes in the inner tube *e*. At the same time, air entering the lower end of the shield *r* around the wick tube *a*, passes through the small

holes in the outer tube *e* into the mixing and combustion chamber *f*, where it and the air entering through the inner tube *e*, mixes and unites with the burning vapors and gases produced by and rising from the burning wick, the oil or liquid fuel being supplied to the flame by the capillary action of the wick in the usual manner. The combustion of the fuel vapor or gas generated by the burning oil or liquid fuel at the upper end of the wick with the heated or warm air supplied thereto through the perforations in the tubes *e*, produces an intensely hot blue flame, which issues from the combustion chamber through the contracted opening in the upper end of the shield *r*. A portion of the air drawn into the lower end of the tube *j* escapes therefrom through the vent openings *l* in the upper head *h* into the central portion of the flame, further aiding combustion of the fuel. The metal walls of the upper section of the burner soon become heated and impart heat to the air which is drawn into the lower end of the tube *j* and the lower end of the shield *r*, and which passing through the small distributed holes in the tubes *e*, is thoroughly mixed with the burning fuel vapor or gas generated in the lower end of the chamber *f*, thereby producing complete combustion and an intensely hot blue flame at the upper end of the combustion chamber.

When the burner is not in use, the upper section is lifted out of contact with the burner tube and locked in an elevated position, as shown in Fig. 2, by depressing the front or outer end of the lever *z* and drawing the operating and locking piece *3* forward into engagement with the base *b*. This prevents oil or liquid fuel from collecting on the lower ends of the tubes *e* and producing smoke and odor when the burner is lighted. In this position of the upper section the upper end of the wick and wick tube are accessible for cleaning and lighting.

Various changes in minor details of construction and arrangement of parts may be made without departing from the principle and scope of the invention as defined in the following claims.

I claim:

1. In a liquid fuel burner the combination with a lower vapor or gas generating section, of an upper section comprising coaxial perforated tubes, forming an annular mixing and combustion chamber, heads engaging the ends of the inner tube, the lower head having an air inlet opening, and a vertical rod connecting said heads and tying them together in engagement with the inner tube.

2. In a liquid fuel burner the combination with a lower vapor or gas generating section, of an upper section comprising coaxial perforated tubes forming an annular mix-

ing and combustion chamber, a central air tube of smaller diameter than and coaxial with the inner perforated tube, and having an air inlet opening at its lower end, heads 5 engaging the ends of the inner perforated tube and the air tube and closing the space between them, and a vertical rod connecting said heads and tying them together, said air tube having an opening above and adjacent to the lower head.

3. In a liquid fuel burner the combination with a lower vapor or gas generating section, of an upper section comprising coaxial perforated tubes forming an annular mixing and combustion chamber, the inner tube having an imperforate belt adjacent to its upper end, and heads engaging the ends of the inner tube and confining it in place, the lower head having an air inlet opening.

20 4. In a liquid fuel burner the combination with a lower vapor or gas generating section, of an upper section comprising coaxial perforated tubes forming an annular mixing and combustion chamber, a central air tube coaxial with the perforated tubes, heads engaging the ends of the inner perforated tube and the air tube and closing the annular space between them, an extension of the air tube depending from the lower head and having an air inlet opening in the side, said air tube having an opening in the side above and adjacent to the lower head, and a vertical rod connecting the upper head and the extension at the lower end of the air tube 25 and tying the heads, inner perforated tube and air tube, together.

5. In a liquid fuel burner the combination with a lower vapor or gas generating section comprising a double walled wick tube, of an 40 upper section comprising coaxial perforated tubes forming an annular mixing and combustion chamber registering at its lower end with said wick tube, the outer tube being perforated approximately from end to end 45 and the inner tube having an imperforate portion adjacent to its upper end, a central air tube, heads engaging the ends of the inner perforated tube and the air tube and closing the space between them, an extension of the air tube depending from the 50 lower head and having a lateral air inlet

opening, the upper head having an air vent opening communicating with the upper end of the air tube and the air tube having a side opening above and adjacent to the lower head, and a vertical rod connecting the upper head with said extension and tying the heads, inner perforated tube and air tube together.

6. In a liquid fuel burner the combination with a fixed lower section comprising a double walled wick tube, of a vertically movable upper section comprising coaxial perforated tubes forming an annular mixing and combustion chamber adapted to register 60 at its lower end with the wick tube, a shield surrounding said tubes at a distance from the outer tube and secured therewith to the inner tube, a central air tube, heads engaging the inner perforated tube and the air 65 tube and closing the space between them adjacent to their ends, an extension of the air tube depending from the lower head and having an air inlet opening, said air tube having a side opening above and adjacent to 70 the lower head, and a vertical rod tying said heads together in engagement with the inner perforated tube and the air tube and guided longitudinally in the wick tube.

7. The combination with a base, a liquid 80 fuel burner comprising a fixed wick tube mounted on said base and provided with a guide, a vertically movable section comprising coaxial perforated tubes forming an annular mixing and combustion chamber 85 adapted to register at its lower end with the wick tube, heads engaging the ends of the inner perforated tube, a vertical rod tying said heads together in engagement with said inner tube and projecting downwardly 90 through said guide, a lever fulcrumed to said base and arranged to engage with the lower end of said rod for lifting said movable section, and an operating piece pivoted to said lever and having a shoulder adapted 95 by engagement with the base to hold the movable section in an elevated position.
